(57) **CLAIM**

I claim the ornamental design for a data transmission cable, as shown and described.

DESCRIPTION

FIG. 1 is a perspective view of a data transmission cable; FIG. 2 is a second perspective view of a data transmission cable;

FIG. 3 is a third perspective view of a data transmission cable; FIG. 4 is a front elevation view of a data transmission cable; FIG. 5 is a bottom plan view of a data transmission cable; FIG. 6 is a top plan view of a data transmission cable; and, FIG. 7 is a right side elevation view of a data transmission cable, the mirror of which constitutes a left side elevation view of the same.
